US0D1098700S

(12) United States Design Patent (10) Patent No.: US D1,098,700 S
(45) Date of Patent: * Oct. 21, 2025

(54) SHOE

(71) Applicant: NIKE, Inc., Beaverton, OR (US)

(72) Inventor: Hector Gonzalez, Beaverton, OR (US)

(73) Assignee: NIKE, Inc., Beaverton, OR (US)

() Term: 15 Years

(21) Appl. No.: 29/932,755

(22) Filed: Mar. 15, 2024

(51) LOC (15) Cl. 02-04

(52) U.S. Cl.

USPC D2/953; D2/951

(57)

CLAIM

The ornamental design for a shoe as shown and described.

DESCRIPTION

FIG. 1 is a bottom view of a shoe showing my new design; FIG. 2 is a bottom front perspective view thereof; and,

FIG. 3 is a bottom rear perspective view thereof.
The broken lines and unshaded regions depicting the remainder of the shoe form no part of the claimed design.

1 Claim, 3 Drawing Sheets
